(57) **CLAIM**

The ornamental design for a photoelectric sensor, as shown and described.

DESCRIPTION

FIG. 1 is a front perspective view of a photoelectric sensor; FIG. 2 is a rear perspective view thereof; FIG. 3 is a front elevational view thereof; FIG. 4 is a rear elevational view thereof; FIG. 5 is a right side view thereof, the undisclosed left side view being a mirror image thereof; FIG. 6 is a top plan view thereof; FIG. 7 is a bottom plan view thereof; FIG. 8 is a front perspective view thereof in an opened position; FIG. 9 is a rear perspective view thereof in the opened position; and, FIG. 10 is a front elevational view thereof in the opened position.
The broken lines depict environmental subject matter only and form no part of the claimed design.
